CLAIM

The ornamental design for a suitcase, as shown and described.

DESCRIPTION

FIG. 1 is a front, top, right side perspective view showing my new design for a suitcase;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a rear, bottom, left side perspective view thereof;
FIG. 9 is an enlarged view of the portion of the suitcase
encircled in FIG. 1;
FIG. 10 is an enlarged view of the portion of the suitcase
encircled in FIG. 1; and,
FIG. 11 is an enlarged view of the portion of the suitcase
encircled in FIG. 8.

The broken lines shown in FIGS. 1 and 8-11, which form no part of the claimed design, encircle portions of the suitcase that are illustrated in enlargements.

1 Claim, 11 Drawing Sheets
